UNITED STATES PATENT OFFICE.

HERMAN BERKOWSKI, OF ZIELENZIG-OSTROW, GERMANY.

BOW FOR STRING INSTRUMENTS.

Application filed July 28, 1927, Serial No. 209,118, and in Germany August 4, 1926.

My invention relates to improvements in bows for string-instruments and particularly to bows having a movable hand lever attached to the bow handle by which lever the tension 5 of the hair bundle of the bow may be varied during playing so as to enable the player to play one or a number of strings at the same time. A pulling element, preferably a cord, connecting the hand lever with the hair- 10 bundle is slidably guided on the former in order to secure smooth movements when the hand lever is actuated and insuring quick and reliable change of the tension of the hair- bundle.

15 In the accompanying drawing the invention is shown by way of example.

Fig. 1 shows the new bow in elevation, Fig. 1^a is an enlarged view of the tensioning end of the bow,

20 Fig. 2 is a side view to Fig. 1 on an enlarged scale, Fig. 2^a is a top view thereof,

Fig. 3 shows the handle part of another construction, Fig. 3^a is a top view thereof.

As shown in Figures 1 and 2 the bow has a 25 curved bow element 1, to the left end of which the bundle of hairs 2 is attached in a known manner. The right bow end bears a roller 3 over which the hairs 2 are guided and tensioned. A bell crank lever 5 is slidably 30 mounted on the handle 4 of the bow rod 1. Between the end of the latter and the upper end of the lever 5 a wire 6 is provided. The arm 7 of the bell crank lever 5 serves as a key which is acted upon by the player. A fork-shaped part 8 of the bell crank lever 5 rides 35 on the handle 4 of the bow rod 1, both its fingers are connected by a cross piece 9. The traverse 10 of a yoke 11 passes through the fork-shaped part 8 in such a manner, that it rests on the upper side of the handle 4. The 40 ends of the yoke 11 are provided with abutments 12. Pulling cords 13 and 13' respectively are passed round each shank of the yoke 11. The ends of these cords are attached at 45 14 to the hairs 2 and at 15 to the underside of the handle 4.

When the key 7 on the bell crank lever 5 is 50 depressed, it is kept in the illustrated position and consequently the bundle of hairs 2 is stretched, as shown. In order to loosen the bundle of hairs for the purpose of touching a number of strings of the instrument the player has only to loosen the key as much as necessary, thus enabling the bell crank lever 55 5 to turn about the traverse 10 of the yoke 11 and to slide along the handle 4. During

this movement of the bell crank lever 5 the cords 13, 13' slide downward on the shanks of the yoke 11, whereby the hairs 2 of the bow are loosened. At the reverse movement 60 of the bell crank lever 5 the cords 13, 13' will slide upwards on the said shanks. In any position of the key 7 and the bell crank lever 5, the cords 13, 13' assume automatically their 65 most favourable position with regard to the bundle of hairs.

According to Figure 3 a bell crank lever 16 is movably connected by a link 17 to the handle 4 of the bow rod 1. Besides this lever 16 is guided by a pin 18 sliding in a slot 19 of the handle 4. The lower arm 20 of the bell 70 crank lever 16 is fork-shaped too. Both fingers of the fork embrace the handle 4 and are connected with each other by a cross piece 21. Each fork finger is provided with a slot 22 in which the pins 23 of a roller 24 slide. Round this roller 24 passes a pulling cord 25, one end of which is attached at 26 to the hairs 2 and the other end to a roller 27. This roller 27 is mounted on the underside of a block 28 75 sliding on the handle 4. A screw spindle 29 provided with a milled head 30 and secured against axial movement passes through the block 28, so that the latter may be adjusted 80 for regulating of the hair-tension.

The manner of manipulating of the device 85 shown in Figure 3 is the same as described with regard to the device shown in Figures 1 and 2. When pressing the key 7 of the bell crank lever 16 the pin 18 slides along the slot 19 to the right. At the same time the pins 23 of the roller 24 travel upward in the slots 22 of the fork 20, so that the loosened hairs 2 are tensioned. When the bell crank lever 16 is released the roller 24 slides downwards 90 whereby a loosening of the hairs is obtained.

I claim:

1. Bow for musical string-instruments, comprising a bow rod, a bundle of hairs, a bell crank lever movably mounted on the handle of the bow, a pulling element connecting said bell crank lever with the bundle of hairs and means by which the said pulling element is caused to slide on the said bell crank lever and longitudinally along one shank thereof, when the latter is acted upon.

2. Bow for musical string-instruments, comprising a bow rod, a bundle of hairs, a bell crank lever movably mounted on the handle of the bow and a pulling cord passed over a roller bodily movable on the bell crank lever, said pulling cord being connected

at one end to the bundle of hairs and at the other end to the handle of the bow rod.

3. Bow for musical string-instruments, comprising a bow rod, a bundle of hairs, a bell crank lever movable mounted on the handle of the bow and a pulling cord passed over a roller displaceably held on the bell crank lever, said pulling cord being connected at the one end to the bundle of hairs and at 10 the other end to a stretching device arranged on the handle of bow rod.

4. Bow for musical string-instruments, comprising a bow rod, a bundle of hairs, a bell crank lever movably mounted on the handle of the bow and a pulling cord passed over a roller movably held on the bell crank lever, said pulling cord being connected at the one end to the bundle of hairs and at the other end to a stretching device arranged on the

handle of bow rod, a slot in the handle, said 20 bell crank lever being bodily movable in the slot of the handle and movably connected thereto by a link.

5. Bow for musical string-instruments comprising a bow end, a bundle of hairs 25 therefor, a bell-crank lever slidable along said rod and having a slot in one end, a link pivotally connecting the lever and rod, a roller mounted in the slot and movable therealong, a tension block slidable in the rod, 30 means to move the block to initially tension the hair, and a flexible tensioning member connected to one end of the hair bundle, passing around said roller and connected to said block.

In testimony that I claim the foregoing as my invention, I have signed my name.

HERMAN BERKOWSKI.
